No. 741,423.

PATENTED OCT. 13, 1903.

F. W. WEEKS.
COMPOSITOR'S STICK.
APPLICATION FILED JAN. 15, 1903.

NO MODEL.

UNITED STATES PATENT OFFICE.

FRANK W. WEEKS, OF SAN ANTONIO, TEXAS.

COMPOSITOR'S STICK.

SPECIFICATION forming part of Letters Patent No. 741,423, dated October 13, 1903.

Application filed January 15, 1903. Serial No. 139,131. (No model.)

To all whom it may concern:

Be it known that I, FRANK W. WEEKS, a citizen of the United States, residing at San Antonio, in the county of Bexar and State of Texas, have invented certain new and useful Improvements in Compositors' Sticks, of which the following is a specification, reference being had therein to the accompanying drawings.

10 My invention relates to improvements in mechanism for setting type and printing therefrom, and is particularly designed to be employed in connection with a type provided upon one end with a printing character and 15 upon its opposite end with a corresponding proof character.

The object of the invention is to provide means for rapidly and easily setting type and printing therefrom by an unskilled person; 20 and to this end it includes, primarily, a combined compositor's stick and chase constructed and arranged as will be hereinafter described, and particularly pointed out in the claims.

25 While the invention is susceptible of various modifications, I have illustrated in the accompanying drawings and shall hereinafter describe what I now conceive to be the preferred embodiment of the same.

30 In the drawings, Figure 1 is a perspective view of the improved compositor's stick and chase. Fig. 2 is a plan view of the same, and Fig. 3 is a transverse sectional view.

In the construction of type in connection 35 with which the present invention is primarily intended to be employed a proof-letter is arranged upon the opposite end of the body to that which carries the printing character, and a shoulder is provided on one side of the body 40 adjacent to its proof end. In setting the required matter the proof ends of the type are held toward the compositor, so that when the form is completely set it may be easily read by an unskilled person without the necessity 45 of securing a proof, as the proof characters are all positively presented. A type of the character referred to is designated by the letter *a*, and the shoulder referred to is indicated by the letter *b*.

50 My improved combined compositor's stick and chase includes a body having a plurality of equidistantly-spaced slots extending en-

tirely through the thickness of the same each of approximately the width of the type. In setting the form the type are inserted in the 55 slots and the lines justified and locked in position by ordinary slugs. The type are dropped in the slots with their proof ends uppermost, and the shoulders *b* thereof engage with the edges of said slots to prevent the 60 type passing entirely through the latter.

Ordinarily after the matter is set in a compositor's stick the same is transferred to the chase to make up the complete form; but it is my purpose to utilize the body in which the 65 type are first set as a chase. For this purpose means are associated therewith which will form a bed for the type to rest against when the form is completely set up, said means being displaceable, so as not to interfere with 70 the placing or setting of the type in the slots. The body is designated in the accompanying drawings by the letter *c* and is shown as provided with a plurality of equidistantly-spaced slots *d*, approximately in width the 75 thickness of the type to be set therein. The upper face of the body *c* is recessed, as shown at *e*, leaving intact marginal strips *f* along opposite edges of the body, the inner walls *g* of said strips being approximately of the same 80 or greater heights than the lengths of the type, which project above the face of the body when said type are set in the slots with their shoulders *b* resting against the edges of the same.

85 Associated with the body *c* is a plate *h*, designed to provide a backing for the type set in the body or a bed against which the proof ends of the type rest, so an impression may be taken from the printing ends thereof. This 90 plate *h* is displaceably mounted in the body or connected thereto, so that when the type are being set the plate may be shifted, so as not to obstruct the entrance to the slots. One means for so mounting this plate is illustrated 95 in the accompanying drawings, in which the same is shown as hinged at one edge to the wall *g* of one of the strips *f*, while the opposite edge of said plate has a detachable engagement with a catch *m*, secured to the wall 100 *g* of the opposite strip *f*. After the form is set this plate is thrown down to bring its free edge beneath the catch *m*, in which position its under face will bear against and form a

bed for the proof ends of the type. The body *c* is then prepared to be placed in any desired construction of press, the plate *h* sustaining the type when impressions are being secured 5 from the printing-faces of the same. The plate *h* is preferably so positioned that when down in place its outer face will be flush with the faces of the strips *f*.

The construction and operation of my invention will be readily understood upon reference to the foregoing description and accompanying drawings, and it will be appreciated that the parts and combinations recited may be varied within a wide range without departing from the spirit of the same. 15

Having thus described my invention, what is claimed as new, and desired to be secured by Letters Patent, is—

1. A combined compositor's stick and chase, 20 comprising a body having a plurality of par-

allel elongated slots extending through the same, and a freely-shiftable displaceable backing-plate associated with said body.

2. A combined compositor's stick and chase including a body having a plurality of receiving-slots, a recessed face and a backing-plate arranged to occupy said recess, substantially as described. 25

3. A combined compositor's stick and chase including a body having a plurality of receiving-slots, a recessed face, and a backing-plate pivoted to one of the side walls of the recess and having a detachable engagement with the opposite side wall, substantially as described. 30

In testimony whereof I affix my signature 35 in presence of two witnesses.

FRANK W. WEEKS.

Witnesses:

MARY E. THAYER,
G. S. MCFARLAND.
